UNITED STATES PATENT OFFICE.

JOHN T. SLOCOMB, OF PROVIDENCE, RHODE ISLAND, ASSIGNOR TO J. T. SLOCOMB COMPANY, OF PROVIDENCE, RHODE ISLAND, A CORPORATION OF RHODE ISLAND.

THREAD-MICROMETER.

1,291,211.

Specification of Letters Patent. Patented Jan. 14, 1919.

Application filed June 11, 1917. Serial No. 173,964.

To all whom it may concern:

Be it known that I, JOHN T. SLOCOMB, a citizen of the United States, residing at Providence, in the county of Providence and State of Rhode Island, have invented 5 certain new and useful Improvements in Thread-Micrometers, and I do hereby declare the following to be a full, clear, and exact description of the invention, such as 10 will enable others skilled in the art to which it appertains to make and use the same.

The present invention relates to micrometers, and more particularly to micrometers for measuring the diameter of threaded 15 work.

The object of the present invention is to devise a micrometer for making accurate measurements of threaded work throughout a wide range both as to diameter and size of 20 thread. A further object of the present invention is to improve the accuracy of thread micrometers by providing a thread-engaging anvil which has a limited rotational movement to adjust itself accurately upon the 25 work.

With these and other objects in view, as will hereinafter appear, the present invention consists of the micrometer hereinafter described and more particularly defined in 30 the claims.

In the accompanying drawings which illustrate what is now considered a preferred form of the present invention, Figure 1 is a side elevation of the micrometer; Fig. 2 is a 35 cross section on line 2—2, Fig. 1, looking in the direction of the arrows, and Figs. 3 and 4 are views of the anvil members detached showing their different lengths of stem and sizes of anvil for use upon different diameters of work and sizes of thread.

As shown in Figure 1 the micrometer comprises a substantially U-shaped frame 5 having at one end a cylindrical boss 6 in which is rotatably mounted the threaded micrometer spindle 7 having the tapered thread engaging face 8 and the usual graduated thimble 9.

The opposite end of the frame is provided with a pair of cylindrical bosses 11 and 12 50 in axial alinement with each other and with the micrometer spindle 7. The boss 11 is provided with a cylindrical recess in which is mounted the anvil member 13 carrying a thread engaging anvil 14 on its end toward the micrometer spindle. This anvil, as well

shown in Fig. 4, which illustrates the member detached from the micrometer, comprises a V-shaped notch 15 to receive one of the threads of the work, the outer faces 16 of the side walls of the notch being beveled 60 to prevent interference with the adjacent threads of the work.

The opposite end of the anvil member 13 engages the abutment screw 18 mounted in the internally threaded recess in the boss 12. 65 This abutment screw 18 may be adjusted from time to time, as may be necessary to give true readings of the micrometer, the frame being split as shown in Fig. 2, and a clamping screw 19 being provided for pinching 70 the frame upon the abutment screw 18.

The anvil member 13 may be clamped in fixed position in the boss 11 when the operator so desires by means of the clamping screw 21 and nut 22 having the handle 23. 75

In order to permit the anvil member 13 to have a limited amount of rotation to adjust itself upon the work, and also to prevent the anvil member from accidental displacement a split collar 25 has been provided which 80 may be secured by means of the clamping screw 26 upon the end of the member 13 which projects from the boss 11 toward the abutment screw 18. This collar is provided with a flat face 27 (see Fig. 2) between 85 which and the frame at 28 there is a sufficient clearance to permit a slight rotational movement of the anvil so that it may adjust itself upon the thread of the work, the nut 22 being at such times loosened upon the 90 clamping screw 21 by means of the handle 23.

When the anvil member shown in full lines in Fig. 1 is used, the micrometer is adapted to measure work only slightly less 95 in diameter than the distance shown between the anvil 14 and the contact face 8 of the spindle. In order to permit work of much smaller diameter to be measured, the anvil member 30 shown in Fig. 3 will be substituted, bringing the anvil then into the position shown in dotted outline in Fig. 1. Where the micrometer spindle is graduated in fractions of an inch and has a range of movement of one inch, the anvil members 100 will differ in length by one inch so that the workman may obtain the true dimension of the work by simply adding to the readings of the micrometer spindle the number of inches required for each particular anvil 110.

member. Preferably the notch 31 on the anvil will be of smaller size than in the anvil shown in Fig. 4, for use upon smaller threads, it being the common practice to 5 use a smaller thread upon smaller diameter work.

The operation of my improved micrometer is as follows: An anvil member having been selected in accordance with the 10 diameter of the work and size of thread, the clamping nut 22 is loosened, and the anvil member is inserted in the recess in the boss 11, the end of the member passing through the collar 25 and into engagement 15 with the adjusting screw 18. The anvil member is then turned to bring the notch into substantial alinement with the plane of the frame, and the clamping screw 26 is tightened while the anvil member is held 20 in this position. The correctness of the adjustment of the abutment screw 18 may be tested by means of a standard which is placed between the anvil and the contact face 8 on the micrometer spindle. If the 25 micrometer does not give the exact predetermined reading with this standard, the screw 19 will be loosened and the abutment screw 18 adjusted until the proper reading is secured, when the clamping screw 19 is 30 tightened to prevent change in the adjustment.

The micrometer will be used in the ordinary manner, the notch in the anvil engaging a thread and the micrometer spindle being 35 turned to bring the contact face 8 on the inclined face of two adjacent threads with the proper amount of pressure. Preferably the clamping nut 22 will be loose so that the anvil may rotate slightly to adjust itself 40 upon the work. The reading of the micrometer will then give the true diameter of the threaded work.

While the drawings illustrate, and I have described what is now believed to be the 45 preferred embodiment of the present invention, it is to be understood that it may be embodied in various other forms and arrangements within the limitations defined in the claims.

50 Having thus described the present invention, what is claimed is:

1. In a micrometer, the combination with the frame provided with two axially alined recesses, of the micrometer spindle rotatably 55 mounted in one of said recesses, an anvil member mounted for free rotation without axial movement in the other recess and provided with an anvil having a work engaging notch opposite the end of the 60 micrometer spindle, and means for limiting the

extent of rotational movement of the member and anvil whereby the anvil will be held in position to engage the work and to adjust itself thereon.

2. In a micrometer, the combination with 65 the frame, of the micrometer spindle rotatably mounted therein, and a plurality of interchangeable anvil - carrying members adapted to be mounted in the frame and provided with thread-engaging anvils each 70 having a thread-engaging notch, the size of the notch varying in the different anvils to fit different sizes of thread, and the anvil members being of different effective 75 lengths, the longer members having the smaller notches.

3. In a micrometer, the combination with 80 the frame provided with a plurality of recesses, a micrometer spindle rotatably mounted in one of said recesses, an anvil member mounted for rotation without axial movement in another of said recesses and in axial alinement with the spindle and provided with an anvil and having a notch on its work engaging face, and a collar detach- 85 ably mounted upon said member and arranged to engage the frame to limit the extent of rotational movement of the member where- 90 by the anvil is held in position to engage the work and adjust itself thereon. 90

4. In a micrometer, the combination with a substantially U-shaped frame provided at one end with a pair of axially alined cylindrical bosses, an anvil member rotatably 95 mounted in one of said bosses, an adjustable abutment screw mounted in the other boss and engaging the end of the member, a collar secured to said member between the two bosses to limit the extent of rotational movement of the member, and a micrometer 100 spindle mounted in the other end of the frame.

5. In a micrometer, the combination with the frame, of the micrometer spindle rotatably mounted therein, an anvil member 105 mounted in the frame for rotation without axial movement and provided with a work engaging face shaped to fit the threads of the work, and devices for holding the member from rotation and for permitting rotational movement in either direction and only to a limited extent, whereby the face of the anvil member will be held in position to engage the threads of the work and to adjust itself thereon, said devices being under the control of the operator. 115

JOHN T. SLOCOMB.
